UNITED STATES PATENT OFFICE

2,619,068

ILLUMINATED MULTISCALE DIAL
STRUCTURE

Luiz G. Malheiros, Syracuse, and Lloyd E. Moncif, North Syracuse, N. Y., assignors to General Electric Company, a corporation of New York

Application September 8, 1949, Serial No. 114,502

2 Claims. (Cl. 116—124.4)

1

Our invention relates to an illuminated multi-scale dial structure for electrical indicating instruments and the like, in which the indicia of the various scales are selectively illuminated to indicate a particular scale to be utilized. It may, for example, be incorporated in a multi-band radio receiver.

It is a primary object of our invention to provide an improved illuminated multi-scale dial structure in which only the indicia of selected scales are indirectly illuminated in accordance with the operation of a scale-selecting switch mechanism.

Another object of our invention is to provide an improved multi-scale dial structure in which one selected group of scale indicia are indirectly back-lighted so as to stand out prominently in relief against an illuminated background.

Still another object of our invention is to provide an improved illuminated multi-scale dial structure in which an optical system for illuminating one scale at a time is electrically controlled and has no mechanically-moving parts.

A still further object of our invention is to provide an improved multi-scale dial structure which is simple and economical to construct and which provides a scale assembly which is pleasing in appearance and easy to read.

Another object of our invention is to provide an efficient means for illuminating a multi-scale dial structure which requires a minimum number of light source and maintains a uniform light distribution throughout the selected illuminated scale.

For additional objects and advantages, and for a better understanding of the invention, attention is now directed to the following description and accompanying drawings. The features of the invention believed to be novel are particularly pointed out in the appended claims.

In the drawings:

Fig. 1 is a fragmentary perspective view, partially cut away to show internal details of construction, of a dial structure embodying the invention;

Fig. 2 is a vertical cross-section view of the structure of Fig. 1, looking towards the left at the plane 2—2;

Fig. 3 is a top plan view, partly in section, of the dial structure of Fig. 1; and

Fig. 4 is a simplified circuit diagram of the switching mechanism and power circuits for selectively energizing the electric lamps which illuminate the several scales in the structure of Figs. 1, 2 and 3.

Corresponding elements in the several figures

of the drawings have been designated by corresponding reference numerals.

In Fig. 1, our invention is represented as applied to a dial mechanism for a multi-band radio receiver. The mechanism is supported from a common mounting plate 10 which is adapted to be bolted or otherwise secured to a radio receiver chassis or cabinet. Against the front face of the mounting plate 10 are stacked a plurality of rectangular bars or prisms, 11—17 inclusive, composed of light-transmitting material. As is best seen in Fig. 2, the stack of bars 11—17 is supported on a lower horizontal metal bar 18 and is held against lateral displacement by means of a cover sheet 19 of glass or plastic material. The metal bar 18 and the lower portion of sheet 19 are secured to the mounting plate 10 by means of a plurality of bolts 20, while the upper edge of the sheet 19 is retained by means of a U-shaped metal strip 21 having a rear flange engaging mounting plate 10 and a front flange engaging the upper edge of sheet 19. A narrower strip 22, which may be of resilient material such as rubber or felt, is also positioned on top of the stack, so that the bars may be forced firmly together between strip 22 and metal bar 18.

Each of the plastic bars 11—17 is composed of a light-transmitting material having a high index of refraction, preferably a transparent plastic resin. For example, satisfactory materials for this purpose include polymerized derivatives of methacrylic or acrylic acid, such as the materials known commercially as "Lucite" or "Plexiglas." The front face of each of the bars adjacent the cover sheet 19 is treated to provide a highly efficient light-emerging surface. Preferably, this front face is polished and cemented to the inner surface of sheet 19, this inner surface being translucent. Alternatively, the cover sheet 19 may be transparent and the front face of each bar may be etched or otherwise treated to provide a translucent light-diffusing surface. The remaining three faces of each bar are treated to provide substantially complete internal reflection of light transmitted axially therethrough. This is preferably accomplished by providing highly-polished surfaces on these three faces, and in some cases it may also be desirable to coat these surfaces with a white or silver reflecting material.

As previously mentioned, the cover sheet 19 is translucent or transparent and may be made of glass or a suitable plastic. As shown in Fig. 1, it has a plurality of horizontal scales thereon, each scale being positioned directly in front of one of the plastic bars. The scale markings and numerical indicia may be painted, engraved or embossed

on the sheet, and they are preferably opaque so as to stand out in relief when back-lighted by light emerging through the front face of the adjacent plastic bar.

The movable scale index comprises a narrow vertical strip 26 of glass or plastic material with a vertical index line 27 marked thereon, and supported at its upper edge from a metal bracket 28. The bracket 28 has a pair of apertured, downwardly-extending ears 29 which are slidably supported by a rod 30 mounted in rear of, and parallel to the mounting plate 10. A small rivet 23 is also secured near the lower end of strip 26 with a round head resting on sheet 19. The movable index assembly is thus slidably supported at three points for horizontal movement across the face of the dial sheet 19. It is actuated by means of a cord drive mechanism comprising a pair of pulleys 31, mounted at opposite ends of the plate 10, over which passes a drive cord 32 to which an upwardly-extending ear 33 on the bracket 28 is attached. The drive cord 32 is of course operated by the electrical instrument for which the dial is calibrated, in this case the variable tuning mechanism of the radio receiver (not shown).

For the purpose of illuminating a selected one of the light-transmitting bars 11-17, a corresponding number of electric lamps 35-41 are positioned opposite the respective left-hand ends of the bars. These lamps are conventionally represented as being of the miniature dial type with a single-point bayonet base. The lamps are mounted in a vertical metal strip 42, in sockets suitably provided therein. The ends of the plastic bars adjacent the lamps are perpendicular to the axes thereof and highly-polished so as to provide maximum transmission of light through the ends.

As seen in Fig. 3, the strip 42 is removably secured by thumb screws 43 to an apertured escutcheon plate 44 which is mounted in front of the dial assembly. The plate 44 may have a transparent plastic sheet 45 secured across the aperture, by means of a clamping ring 46 and machine screws 47, in order to protect the dial assembly from dirt and mechanical injury. Individual contact springs 50-56 are suitably mounted so as to make contact with the base contacts of the respective lamps. As shown, the springs 50-56 are secured by means of rivets to an insulating strip 57, which is in turn fastened to the metal bar 42 by means of machine screws 58.

In order that the light from each of the lamps 35-41 may be directed only upon the polished end of the plastic bar which is to be illuminated by it, a metal shielding plate 60 is interposed between the two. As best seen in Fig. 3, the tip end of each of the lamps fits freely into a socket in the plate 60 which communicates with an aperture 61 of reduced diameter and aligned with the axis of the adjacent bar. The shield plate 60 is suitably secured to mounting plate 10, as by welding, and its upper end also supports the flange strip 21. Another shield plate 59 is also similarly mounted at the right-hand end of the dial assembly, as shown in Fig. 3. This plate 59 is not apertured in the illustrated form of the invention, but its inside surface may be polished or coated to reflect back any light emerging through the adjacent polished ends of the plastic bars 11-17, thereby improving the uniformity of scale lighting.

As shown in the simplified circuit diagram of

Fig. 4, a rotary selector switch 62 is provided for selectively energizing any one of the lamps 35-41 from a suitable power source, represented by a transformer 63. The same shaft which actuates the selector switch 62 is also preferably connected to the band-switching mechanism of the receiver. In this way, only the selected scale opposite one of the bars 11-17 is illuminated at any one time. In the drawing, the bar 13 is represented as being illuminated, causing the figures and markings on the adjacent scale to stand out in bold relief and clearly indicating the selected tuning band of the receiver.

It will thus be seen that we have provided a simple and effective means for selecting any one of a plurality of scales on a multi-scale dial structure which requires no mechanically-moving parts. The indirect illumination of the selected scale not only provides a pleasing appearance but minimizes eye strain on the part of the observer.

It will be obvious that numerous modifications may be made in the structure within the scope of our invention. For example, where the indicating scale is relatively long, it may be desirable to provide another set of identical lamps at the opposite ends of the light-transmitting bars in order to provide more uniform illumination throughout the length of each scale. In this case, the shield plate 59 may be identical to plate 60, and the pairs of dial lamps opposite the ends of each bar are then selectively energized in parallel from the power source. In the illustrated form of the invention, in which the scale indicia are carried by the translucent dial sheet 19, it is desirable that this sheet be in close optical contact with the adjacent faces of each of the light-transmitting bars and that it be composed of a plastic material having the same index of refraction to assure that the illuminated area will appear to have clean, sharply-defined edges. However, in certain other modifications, it may be desirable to print, engrave or emboss the scale indicia directly upon the faces of the strips 11-17 themselves, in which instance their faces may themselves be made light-diffusing. It will also be apparent that various color effects may readily be produced by using color filters between the dial lamps and plastic bars, or by using colored lamps, or by making the plastic bars themselves of colored material.

As another modification, the dial surface formed by the front faces of the plastic bars may be curvilinear instead of planar as illustrated. Since these and other obvious modifications will readily occur to those skilled in the art, we therefore desire it to be understood that the appended claims are intended to cover any such modifications within the true spirit and scope of our invention.

What we claim as new and desire to secure by Letters Patent of the United States is:

1. An illuminated multi-scale dial structure comprising a plurality of selectively illuminable elongated parallel prisms of transparent plastic resin material having a high index of refraction, all the faces of each prism being polished so as normally to provide substantially total internal reflection of light transmitted axially therethrough, one face of each of said prisms being contiguously arranged to form a continuous surface, a dial sheet of plastic resin material having substantially the same high index of refraction and having an inner translucent surface in close optical contact with each of said contiguous faces, and a plurality of groups of scale indicia

on said sheet, each group being positioned adjacent one of said contiguous faces and arranged to be illuminated in relief by light diffused through said sheet.

2. An illuminated multi-scale dial structure comprising a plurality of selectively illuminable elongated parallel prisms of transparent plastic resin material having a high index of refraction, all the faces of each prism being polished so as normally to provide substantially total internal reflection of light transmitted axially therethrough, one face of each of said prisms being contiguously arranged to form a contiguous surface, a dial sheet of plastic resin material having substantially the same high index of refraction and having an inner translucent surface cemented in close optical contact with each of said contiguous faces, a plurality of groups of scale

5

indicia on said sheet, each group being positioned adjacent one of said contiguous faces and arranged to be illuminated in relief by light diffused through said sheet.
